(57) **CLAIM**

The ornamental design for a foldable storage pouch, as shown and described.

DESCRIPTION

FIG. 1 is a top, front, left side perspective view of a first embodiment of a foldable storage pouch showing our new design;

FIG. 2 is a top plan view thereof;

FIG. 3 is a front elevational view thereof, the rear view being a mirror image thereof;

FIG. 4 is a right side elevational view thereof, the left side being a mirror image thereof;

FIG. 5 is a bottom plan view thereof;

FIG. 6 is a top, front, left side perspective view of a second embodiment of the foldable storage pouch showing our new design;

FIG. 7 is a right side elevational view thereof, the left side being a mirror image thereof;

FIG. 8 is a top plan view thereof; and,

FIG. 9 is a bottom plan view thereof.

The broken lines showing structural elements in the drawings are included for the purpose of illustrating an environment of use and non-claimed subject matter, and form no part of the claimed design. The broken lines illustrating stitching along the sidewalls, top and bottom of the foldable storage pouch are non-claimed subject matter and form no part of the claimed design.
